COMBINED DINING AND COOKING TABLE

Ron Shimosawa, Chicago, Ill., assignor to
Kiku Co., Chicago, Ill.

Filed June 19, 1970, Ser. No. 23,575

Term of patent 14 years

Int. Cl. D7—02

U.S. Cl. D81—10

FIG. 1 is a front elevational view of a combined dining and cooking table showing my design.

FIG. 2 is a top plan view thereof, and

FIG. 3 is a side elevational view thereof.

The side opposite that shown in FIG. 3 is a mirror image thereof. The rear surface is the same as the front, except for the small circular elements and the cutout, which are shown in the front but do not appear on the rear. The bottom member or bottom plate is circular.

I claim:

The ornamental design for a combined dining and cooking table, as shown and described.
